UNITED STATES PATENT OFFICE.

FRANK MOSSBERG, OF ATTLEBORO, MASSACHUSETTS, ASSIGNOR TO MOSSBERG
PRESSED STEEL CORPORATION, OF ATTLEBORO, MASSACHUSETTS, A CORPORA-
TION OF MASSACHUSETTS.

BOBBIN.

Application filed July 5, 1923. Serial No. 649,502.

To all whom it may concern:

Be it known that I, FRANK MOSSBERG, a citizen of the United States, residing at Attleboro, in the county of Bristol and State of Massachusetts, have invented certain new and useful Improvements in Bobbins, of which the following is a specification.

This invention relates to an improved construction of yarn package holder such as a cop or bobbin, more particularly adapted to be used as a yarn package holder for braiding machines, and has for its object to provide such a package holder preferably formed entirely of metal, the same comprising a tubular body portion having a metal disc-shaped head at one end thereof, which head is provided with a plurality of radially disposed teeth cut at intervals from the stock of the plate and bent down to stand at right angles to the plane of the plate and set radially with respect to its center thereby providing a set of teeth on the head, each of which is the same on both of its opposite faces so as to control the rotation of the holder in either direction when receiving or dispensing yarn.

With these and other objects in view, the invention consists of certain novel features of construction, as will be more fully described, and particularly pointed out in the appended claims.

In the accompanying drawings,

Figure 1 is a side elevation of my improved yarn package holder showing a head on one end of the body portion thereof.

Figure 2 is the same as Figure 1, showing a head on opposite ends of the body portion of the holder.

Figure 3 is a view of the under face of the head of the holder.

Figure 4 is a section on line 4—4 of Figure 3, showing one of the teeth as cut from the stock and projecting downwardly from the face of the plate.

Figure 5 is a section on line 5—5 of Figure 3 illustrating one of the teeth as cut from the stock and turned downwardly at right angles to the face of the plate from which it is cut.

Figure 6 shows the center portion of the head-plate as being turned outwardly to form a collar into which the end of the tubular body is fixed.

It is found in practice of advantage to

provide a yarn package holder entirely of metal, forming a body portion of a piece of tubing and the head of a sheet metal disc; also to form a hub or collar portion from the central portion of the stock of the head and to form a plurality of teeth about the hub by cutting and bending downwardly portions of the stock at intervals, from the face of the head, and in this way form teeth which are set radially with respect to the center of the plate and also teeth whose side faces are set at substantially right angles to the plane of the head-plate, whereby the holder is adapted to be rotated in either direction; and the following is a detailed description of one means by which a device of my improved construction may be made:

With reference to the drawings, 10 designates the body portion of a holder which is preferably formed of a short length of metal tubing, and the head member 11 is also preferably formed of sheet metal cut into disc shape, the middle portion of the disc member being pressed inwardly as illustrated in Figures 1 and 2, as at 12, to form a collar or hub, into which the end of the tube is pressed, or this middle portion may be turned outwardly, if desired, as at 13, see Figure 6, to receive the end of the tube, and this tube may be fixed in this collar by brazing or other desired fastening means.

In order to provide the necessary teeth on this head-plate, I have cut portions of the stock of the plate at intervals about its face and have bent the cut portions outwardly forming teeth 14 which set at right angles to the plane of the face of the head and radially with respect to the center of the head, both faces of these teeth presenting flat surfaces to the engaging pawl (not shown) whereby this holder may be controlled equally well while being rotated in either direction, which is of advantage particularly when called upon to operate in certain kinds of machines.

It is also found of advantage to punch or cut these teeth from the stock of the plate so that their outer edges 15 will set a short distance inwardly from the periphery of the plate so as to leave a continuous, unbroken ring about the periphery of the plate, which construction strengthens the teeth and offers the minimum weakening effect to the head-plate.

In some instances, the tube is provided with a plurality of ribs 16 arranged about its periphery by forcing outwardly portions of the stock of the tubing, for retaining a paper ⁵ cap when positioned on the holder.

My improved construction of holder is very strong and durable, is simple and practical, and is effective in its operation.

The foregoing description is directed solely ¹⁰ towards the construction illustrated, but I desire it to be understood that I reserve the privilege of resorting to all the mechanical changes to which the device is susceptible, the invention being defined and limited only ¹⁵ by the terms of the appended claims.

I claim:

1. A yarn package holder having a tubular body portion and a metal disc-shaped head-plate secured to one end thereof, said ²⁰ plate having radially-disposed spaced-apart relatively broad faced teeth cut from the stock of the plate and bent down from the plane thereof into operating position, the outer edges of the teeth being spaced a short

distance inwardly from the periphery of ²⁵ said head-plate.

2. A yarn package holder having a tubular body portion to one end of which is secured a sheet metal disc plate having a plurality of radially disposed relatively broad faced teeth cut at intervals from the stock of the plate with their outer edges spaced a short distance inwardly from the periphery of the plate and bent down to stand in a plane at right angles to that of said plate. ³⁰ ³⁵

3. A yarn package holder having a tubular body portion, a metal disc-shaped head-plate having a collar formed from the stock of its center portion of said plate in which the end of said tube is fixed, said disc-plate ⁴⁰ having a plurality of radially disposed relatively broad faced teeth cut at intervals from the stock of the plate and bent to stand at right angles to the plane of the plate.

In testimony whereof I affix my signature.

FRANK MOSSBERG.
